ROTARY CLEANING BRUSH

Earl Dallas Smith, Scottsdale, Ariz., assignor to Southern Pacific Land Company, San Francisco, Calif., a corporation of Delaware

Filed Dec. 29, 1966, Ser. No. 5,228

Term of patent 14 years

(Cl. D9—2)

Fig. 1.

Fig. 2.

Fig. 3.

FIG. 1 is a perspective view of a rotary cleaning brush, showing my new design.

FIG. 2 is a top plan view thereof.

FIG. 3 is a bottom view thereof.

The side not shown is substantially like the side shown. The broken lines shown on the drawing are for illustrative purposes only.

I claim:

The ornamental design for a rotary cleaning brush, as shown and described.
